UNITED STATES PATENT OFFICE.

PIETER DE LANGE AND ROBERT AERNOUT BARON VAN LYNDEN, OF UTRECHT, NETHERLANDS, ASSIGNORS TO NAAMLOOZE VENNOOTSCHAP DE NEDERLANDSCHE THERMO-TELEFOON MAATSCHAPPIJ, OF UTRECHT, NETHERLANDS, A CORPORATION OF NETHERLANDS.

PROCESS FOR THE MANUFACTURE OF HEATING ELEMENTS FOR THERMIC TELEPHONES.

1,246,065.

Specification of Letters Patent.

Patented Nov. 13, 1917.

Application filed November 4, 1915. Serial No. 59,624.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented a new and useful Process for the Manufacture of Heating Elements for Thermic Telephones, of which the following is a specification.

10 Our invention relates to a process for the manufacture of heating elements for thermic telephones from Wollastone wires, and has for its object to arrange as many arch-shaped wires as possible on a heating conductor support of a given size, as is required for insuring a favorable sound effect.

According to this invention, this is accomplished by the adjoining branches of the arch-shaped Wollastone wires being embedded close together in recesses of the heating conductor support made of insulating material, and then subjected in the well known manner to etching at their portions projecting from the support.

25 In this way it is possible to obtain an exceedingly close or compact arrangement of the arch-shaped heating wires to be formed into a heating conductor, as the method of embedding the wires in the support insures 30 that the feet or bases of the adjoining heating wires—which project from the support to an extent equal to the length of the sound producer—are at a very small distance from each other, viz: a distance equal to the 35 double thickness of their coating. If, for instance, Wollastone wires 0.48 mm. in diameter are used, the platinum core of which is only 0.005 mm. in diameter, the cores of the wires will have a distance apart of 40 0.475 mm. if the wires are so placed that they are in contact with each other at their bases.

45 Reference is to be had to the accompanying drawings, in which two forms of heating elements manufactured according to the present process are shown by way of example on an enlarged scale, Figure 1 being a perspective view (with parts in section) of one form, and Fig. 2 a sectional view of the 50 other form.

In the heating element shown in Fig. 1,

1 is the heating conductor support of insulating material, for instance vulcanized rubber or ebonite. On the upper surface of the support 1 are provided recesses 2 in which the branches 3 of the arch-shaped heating wires joined together below in the form of loops, are secured in such a manner that the adjoining branches are quite close together. The portion 4 of the heating wires, 55 projecting from the support 1 and corresponding to the desired length of sound producer, is then subjected in the well known manner to etching, whereby the fine platinum cores are exposed. It follows that these 60 cores, at their bases 6, are at a distance equal to double the thickness of the wire coating, whereby partial short circuits between the platinum wires are rendered impossible. In practice, the arches 4 are not 65 etched quite down to their support 1 but a portion of their coating is left at the bases 6 so that the acid is not drawn into the embedded portion 3 by capillary action.

In the modification illustrated in Fig. 2 75 the heating wires are not continuous but formed of separate loops 10 the branches 9 of which are embedded close together in recesses 8 of a support 7. Those branches 11 which are at the outside of the conductor, 80 are carried through perforations 12 in the same. The etching of the heating wire loops is effected in the manner above described.

We claim:

1. The process for the manufacture of 85 heating elements for thermic telephones from Wollastone wires, consisting in embedding the ends of adjoining loops contiguously in recesses of a support, and etching the looped portions for the desired sound 90 producer length.

2. The process for the manufacture of heating elements for thermic telephones from Wollastone wires, consisting in bending a continuous wire to form a plurality 95 of arches and doubled up bends, embedding said bends in recesses of the heating conductor support with the members of the bends in mutual contact, and etching said arches for the desired sound producer 100 length.

3. The process for the manufacture of

heating elements for thermic telephones from Wallastone wires, consisting in embedding the ends of adjoining loops in contact with each other, within recesses of a support, and etching the looped portions for the desired sound producer length and

leaving unetched a portion of the wires at the face of the support.

In testimony whereof we have signed this specification.

PIETER DE LANGE.

ROBERT AERNOUT BARON VAN LYNDEN.
